DEMOUNTABLE BEAM COMPASS

Clarence M. Woodward, Washington, D. C.

Application November 1, 1949, Serial No. 124,936

3 Claims. (Cl. 33—27)

(Granted under the act of March 3, 1883, as
amended April 30, 1928; 370 O. G. 757)

1

The invention described herein may be manufactured and used by or for the Government of the United States for governmental purposes without payment to me of any royalty thereon in accordance with the provisions of the act of April 30, 1928 (ch. 460, 45 Stat. L. 467).

This invention relates to a drafting instrument of the "beam compass" type and particularly to one which includes a pen of the "bow compass" type, a wooden rectangular bar, a spring clip for detachably fastening said compass to said bar and a second spring clip provided with an adjustable clamp for a needle which forms a pivot.

In the accompanying drawing which illustrates a preferred embodiment of my invention:

Figure 1 is a side elevation of my assembled instrument.

Figure 2 is a detail of a compass mounting clip.

Figure 3 is a detail of a companion pivot mounting clip.

Figure 4 is a cross-section of a clip.

Figure 5 is a cross-section on line 5—5, Figure 3.

In these drawings:
A U-shaped clip 10 is formed of resilient sheet metal with one leg 12 longer than the companion leg 11 and with a triangular shaped prong 13, the use of which will be disclosed later in this specification, and a rectangular punching 14 bent into an L shape for attaching a channel member 15 to the face of the clip 10. The detachable channel member 15 is provided with a transverse threaded hole 16 for receiving a set screw 17, by means of which the pivot leg 18 of a bow compass 19 is rigidly attached to the clip 10. A second spring clip 20 is provided with a sleeve member 21 corresponding to the channel member 15 provided with a guiding hole for a pivot pin 22 and a transverse threaded opening for a clamping set screw 23.

The spring clip 20 is also provided with a detachable base member 24 to which it is secured by an L-shaped punching 25. The base member 24 is also provided with two hemispherical feet 26 which serve to hold my device in an upright position.

A wooden beam 27 is resiliently engaged by the clips 10 and 20 when the prongs 13 of each clip imbed themselves in the wooden beam at points selected by the operator. The wooden beam 27 may be formed in sections which are detachably united by a spring clip 28 provided with two prongs 13.

My beam compass is designed for easy demounting and for compact storage while utilizing a bow compass of common form for the marking element. While a bow pen is illustrated in the drawings a bow pencil may be readily substituted for drawing a penciled line.

It should be understood that the present disclosure is for the purpose of illustration only,

and that the invention includes all modifications and equivalents which fall within the spirit and scope of the appended claims.

What I claim is:

5 1. A drafting compass comprising a beam, a resilient U-shaped clip provided with an inturned prong in a channel wall and an outward projection from a channel wall, a clamp for rigidly mounting a drafting instrument on said outward projection, a second resilient clip provided with an inturned prong in a channel wall and with a downward projection for coupling with a base member, and a slotted base member adapted for detachably receiving said projection and provided with a pivot clamp and a plurality of supporting feet.

10 2. A beam compass forming attachment comprising a U-shaped spring clamp provided with an inwardly projecting prong and a downward projection for attaching a base member, and a slotted base member adapted for detachably receiving said projection, a pivot clamp rigidly mounted on said base member, and a plurality of supporting feet mounted on said base member.

15 3. A drafting compass comprising two beam sections, a resilient U-shaped coupling clip provided with inturned prongs for uniting said beam sections, a resilient U-shaped clip provided with an inturned prong and an outward projection, a clamp for rigidly mounting a drafting instrument on said outward projection, a third resilient clip provided with an inturned prong and with a downward projection for detachably securing a slotted base member, and a slotted base member provided with a pivot clamp and a plurality of supporting feet.

CLARENCE M. WOODWARD.
